UNITED STATES PATENT OFFICE.

JOSEPH R. LANCASTER, OF NEW YORK, N. Y., ASSIGNOR TO JORDAN L. MOTT, OF SAME PLACE.

DESIGN FOR WASH-BASIN.

Specification forming part of Design No. 7,466, dated June 2, 1874; application filed May 1, 1874.
[Term of Patent 7 years.]

CASE A.

To all whom it may concern:

Be it known that I, JOSEPH R. LANCASTER, of the city, county, and State of New York, have invented a new and original Design for a Wash - Basin, of which the following is a specification:

The design is fully represented in the accompanying photographic illustration, and relates to the form and ornamentation of the back and top of the sink.

The vertical back is straight on the upper side to the point *a*, where it rounds or curves abruptly downward to a horizontal step or shoulder, *c*, whence it descends, by curves, in a general diagonal direction, to meet the top *B*. Said edge is rounded, in the form of an ovolو molding, and is rabbeted on the front side, as shown. The top *B* has a bead or astragal molding, *e*, and a scotia - shaped molding below the same, forming the edge. Its

general contour is circular. Its upper surface, around the cavity of the bowl, as well as the face of the back portion *A*, may be plain or ornamented, as preferred.

I intend the bowl *c* to constitute the subject of separate Letters Patent.

I do not claim, broadly, the design shown; but

I claim—

1. The design for the back of the sink, having the ovolو molding around the edge, and the form specified at *a e*, as shown.

2. The design for the top of the sink, having the bead and scotia - shaped molding around the edge, as shown.

JOSEPH R. LANCASTER.
